CARVING KNIFE

Emil S. Polk, Scarsdale, N. Y.

Application November 8, 1954, Serial No. 33,005

Term of patent 14 years

(Cl. D54—12)

To all whom it may concern:

Be it known that I, Emil S. Polk, a citizen of the United States of America, residing at Scarsdale, county of Westchester, State of New York, have invented a new, original, and ornamental Design for a Carving Knife, of which the following is a specification, reference being had to the accompanying drawing, forming part hereof.

Figure 1 is a side elevational view of a carving knife embodying my new design;

Figure 2 is a top plan view of the carving knife with a portion of the blade element broken away for convenience of illustration;

Figure 3 is a bottom plan view thereof with a portion of the blade broken away for convenience of illustration;

Figure 4 is a sectional view as seen from the plane 4—4 on Figure 1; and

Figure 5 is a sectional view as seen from the plane 5—5 on Figure 1.

I claim:

The ornamental design for a carving knife, as shown and described.
